CLAIM

The ornamental design for an integral lid and seal for a container, as shown and described.

DESCRIPTION

FIG. 1 is a front perspective view, from above, of the claimed design;

FIG. 2 is a rear perspective view, from below, of the claimed design;

FIG. 3 is a top plan view of the claimed design;

FIG. 4 is a bottom plan view of the claimed design;

FIG. 5 is a front elevational view of the claimed design, the rear elevational view being a mirror image;

FIG. 6 is a left side elevational view of the claimed design, the right side elevational view being a mirror image;

FIG. 7 is a sectional view of the claimed design taken along the line 7-7 of FIG. 3;

FIG. 8 is an enlarged fragmentary view of the portion of the design designated by the discontinuous circle and the number 8 in FIG. 7;

FIG. 9 is a sectional view of the claimed design taken along the line 9-9 of FIG. 3; and,

FIG. 10 is an enlarged fragmentary view of the portion of the design designated by discontinuous circle and the number 10 in FIG. 9.

The purpose of broken lines in the drawing is to illustrate an optional vent that forms no part of the design to be patented.
